Primary Examiner—Clare E Heflin

CLAIM

The ornamental design for a chandelier, as shown and described.

DESCRIPTION

FIG. 1 is a perspective view thereof;

FIG. 2 is a front elevational view thereof;

FIG. 3 is a right side view, the left side being a mirror image;

FIG. 4 is a top view thereof; and,

FIG. 5 is a bottom view thereof.

The broken line showing of environmental structure in FIGS. 1-4 is for illustrative purposes only and forms no part of the claimed design.
